PLATE OR THE LIKE

Mary K. Grant, Los Angeles, Calif., assignor to Gladding, McBean & Co., Los Angeles, Calif.,
a corporation of California

Application August 30, 1952, Serial No. 21,250

Term of patent 14 years

(Cl. D44—15)

To all whom it may concern:

Be it known that I, Mary K. Grant, a citizen of the United States, residing at Los Angeles, county of Los Angeles, and State of California, have invented a new, original, and ornamental Design for a Plate or the like, of which the following is a specification, reference being had to the accompanying drawing, forming part thereof.

Fig. 1 is a plan view of a plate or the like, showing my new design.

Fig. 2 is a fragmentary cross section of the marginal portion of the plate illustrated in Fig. 1.

The design is characterized by a centrally located representation of a shock of wheat upon a background of fine, substantially concentric lines and in spaced relation to a grain of wheat motif border.

I claim:

The ornamental design for a plate or the like, substantially as shown and described.
